UNITED STATES PATENT OFFICE.

CARL EUGENE SIMS, OF EASTLAND, TEXAS.

POWDER EJECTOR.

Original application filed March 15, 1923, Serial No. 625,360. Divided and this application filed June 7, 1924, Serial No. 718,610.

To all whom it may concern:

Be it known that I, CARL EUGENE SIMS, a citizen of the United States, and a resident of Eastland, in the county of Eastland and 5 State of Texas, have invented certain new and useful Improvements in Powder Ejectors, of which the following is a specification.

This invention relates to a powder ejector 10 for use in conjunction with a douche forming the subject-matter of my copending application filed March 15, 1923, Serial No. 625,360, of which the present application is a division.

15 The object of the invention is to provide a powder ejector of this character which is effective to forcibly eject and spray the powder at the proper time while maintaining the powder in a dry state and while protecting the same up to the time of the actual application of the powder.

20 Other objects and advantages of the invention reside in certain novel features of the construction, combination and arrangement of parts which will be hereinafter more fully described and particularly pointed out in the appended claim, reference being had to the accompanying drawings forming part of this specification, and in 25 which:

Figure 1 is a view in vertical section, showing the powder ejector or spray constituting the present invention;

Figure 2 is a plan view of the device 30 shown in Figure 1;

Figure 3 is a view in section on line 3—3 of Figure 1; and

Figure 4 is an enlarged fragmentary view, 35 partly in section and partly in elevation, showing the spring catch of the plunger rod for the powder ejector.

As shown in the drawings, the powder spray or ejector includes a cylindrical barrel 65 divided by partitions 66 into four quadrant compartments 67, two of which are 40 adapted to contain a charge of powder, the other two being idle or inactive in this form of the invention.

In each of the active compartments 45 67 there is fitted a cup-shaped plunger 68. The plungers 68 are secured to the ends of plunger rod 69 which project exteriorly of the barrel 65 and which have their exteriorly projecting portions connected by means of 55 a flange 70 to which an operating knob 71

is fitted to facilitate manipulation of the plungers.

A spring 72 is fitted on each rod 69. One end of each spring 72 abuts a plunger head 68 and its opposite end abuts the lower head 60 of the cylinder or barrel 65 which head is designated at 73. The springs 72 are so tensioned as to tend to move the plungers 68 through the compartments of the barrel and consequently eject or spray the powder. 65

Means is provided for holding the plungers 68 retracted, and as shown in Figure 4 may comprise a single spring catch 75 similar to those used on umbrellas and comparable with the lower head 73 of the barrel. 70 If desired, however, one such spring catch 75 may be mounted in each plunger rod 69.

The end of the barrel or cylinder 65 which is disposed at the outer end of the douche in use is of rounded formation and 75 is provided with a fixed top plate 77 for each of the inactive compartments and rotatable top plates 78 for the active compartments, the rotatable top plates 78 being adapted to be disposed to close the outer 80 ends of the active compartments or to overlie the top plates 77 and thus leave open the top ends of such active compartments. The top plates 78 are connected by an integral hub portion 78^a. Means is provided for operating the rotatable top plate 78 and preferably comprises a rotatable operating rod 79 extending longitudinally of the barrel through a bearing sleeve 80. One end of this rod is fixed to the rotatable top plate 78 and its other end projects below the barrel and is formed with an operating arm 81. The operating arm 81 has integral therewith an operating cam or finger 82 engageable with the catch 75 for releasing the same 95 as will be understood from an inspection of Figure 3.

With this arrangement when the powder is to be ejected the arm 81 is grasped and turned to move the plate 78 so as to uncover 100 the active compartments in which the powder is placed. This automatically releases the plunger rods 69 for the finger 82 releases the catch 75 provided on one of the rods 69 thereby permitting the spring 72 to force the plunger 68 through the compartments to effect discharge or spray of the powder. 105

It is to be understood that if desirable a number of spring catches 75 may be em- 110

ployed along either plunger rod 69 to provide for a variable action. If it should be found desirable to provide a catch 75 on each rod 69 then of course a plurality of 5 fingers 82 would be provided, since it would be necessary to have a finger 82 for each catch.

I claim:

A powder ejector including a barrel, partitions in said barrel dividing the same into

compartments, spring actuated plungers in said compartments, a spring catch for holding said plunger retracted, a rotatable lid for the discharge end of the barrel, and operating means for said lid, said operating means being engageable with the spring catch for releasing the same upon opening 15 of the lid.

CARL EUGENE SIMS.
